(57) **CLAIM**

I claim the ornamental design for an upright handled service tray, as shown and described.

DESCRIPTION

FIG. 1 is a perspective view of the upright handled service tray.

FIG. 2 is a left side elevation view thereof.

FIG. 3 is a front elevation view thereof.

FIG. 4 is a top plan view thereof.

FIG. 5 is a right side elevation view thereof.

FIG. 6 is a rear elevation view thereof; and,

FIG. 7 is a bottom plan view of the upright handled service tray.
